BOX STACKER

James W. Stevenson, Riverside, Calif.

Application January 11, 1937, Serial No. 119,989

6 Claims. (Cl. 214—6)

This invention relates to the art of article handling and particularly to the handling of loaded and empty boxes.

While useful in many industries, this invention is particularly useful in the citrus industry in which fruit is handled in boxes during the harvest and packing of the fruit. For purposes of illustration of the invention, therefore, an embodiment of this designed for use in citrus packing houses is disclosed herein.

Citrus fruits are harvested by being picked from the trees by hand and are brought to the packing house from the groves in what are known as field boxes. At the packing house these loaded boxes are taken from the truck and stacked on the floor in stacks of anywhere from five to eight boxes high. When it is desired to remove the fruit from these boxes and run it through the series of treatments by which it is prepared for market, the fruit of course must be dumped from the boxes containing it and the empty boxes delivered to empty box storage. Clamp trucks are provided by which an entire stack of boxes can be very easily handled and moved from place to place on the packing house floor by a single worker.

It is an object of my invention to provide a machine to which loaded boxes may be delivered in the form of stacks and which will dump the contents from the boxes in these stacks and form the empty boxes into stacks for storage.

In stack dumpers previously in use, there has always been a pause between the dumping of the last box in a given stack and the first box in the next stack which is longer than the interval between the dumping of successive boxes in each stack. This resulted in irregular feeding of fruit to the various machines for treating this, with corresponding decrease in efficiency in these machines.

It is therefore another object of my invention to provide a stack handling device which will deliver individual boxes of a series of stacks successively to a box dumper or other mechanism so that the interval between the delivery of the last box of each stack and the first box in the next succeeding stack is the same as the intervals between the delivery of successive boxes in a given stack.

The stacking of boxes in the citrus industry is not only necessary after the contents have been dumped from the box, but also when the boxes are first received from the groves into the packing house. It is, therefore, another object of my invention to provide a novel and efficient box stacker which may be used either for handling loaded or empty boxes.

The manner of accomplishing the foregoing objects, as well as further objects and advantages, will be made manifest in the following de-

scription taken in connection with the accompanying drawings, in which:

Fig. 1 is a diagrammatic cross sectional view of a preferred embodiment of my invention.

Fig. 2 is a cross sectional view taken on the line 5—2 of Fig. 1.

Fig. 3 is a plan view of the upper portion of Fig. 1 showing the drive mechanism.

Fig. 4 is a side elevational view of Fig. 3 taken in the direction of the arrow 4 and illustrating 10 that portion of the drive mechanism on that side of the machine.

Fig. 5 is a diagrammatic fragmentary detail view of a rest disposed as when supporting a box 15 in dumping position.

Fig. 6 is a cross sectional view taken on the line 6—6 of Fig. 3.

Fig. 7 is an enlarged fragmentary cross sectional view illustrating additional steps to those shown in Fig. 1 of the dumping of a box and just 20 after a new stack has been received into the machine.

Fig. 8 is an enlarged fragmentary cross sectional view of a portion of the apparatus shown in Fig. 1 and illustrating the ejection of a stack 25 just formed and the starting of a new stack.

Fig. 9 is a fragmentary perspective view illustrating a stack forming cradle of the stacker of my invention and the manner in which this operates the stack ejector thereof.

I shall now refer specifically to the drawings in which I show a combined box stack dumper and empty box restacker 10 which includes a frame 11, a loaded stack feed conveyer 12, a stack elevator 13, a box dumping mechanism 14, a conveyer 15 for removing empty boxes from the dumper 14 and delivering these to a stacker 16, and an empty stack discharge conveyer 17.

The stack feed conveyer 12

The stack feed conveyer 12 is mounted in a floor 20 upon which the frame 11 rests and comprises a pair of chains 21 which pass around idle sprockets 22 and drive sprockets 23, the latter being fixed on stub shafts 24 with driven 45 sprockets 25. Provided on the chains 21 are stack spacing lugs 26.

The stack elevator 13

The stack elevator 13 includes an endless chain 50 mechanism 30 having a drive shaft 31, stub shafts 32, and sprockets 33 and 34 fixed on these shafts about which sprockets are trained endless chains 35. Fixed on the shafts 32 and disposed outwardly from the sprockets 34 are drive sprockets (not shown) which are connected by endless chains 39 with the driven sprockets 25 so that whenever the sprockets 34 are rotated by the chains 35, the sprockets 25 are also rotated thus setting in motion the box stack feed conveyer 12. 60

The chain mechanism 30 is mounted so as to be inclined away from the stack conveyer 12.

The space just in advance of endless chain mechanism 30 may be termed a stack elevating path 36. Bordering this path and located between the endless chains 35 just back of the path 36 is an inclined back plate 37 which is supported on the frame 11 by members 38. Also mounted on the frame 11 and extending substantially parallel with the foremost flights of the chains 35 are guides 41. Back of the chains 35 are provided guides 45 which are secured upon the frame 11.

The stack elevator 13 also includes two stack lifting cradles 47 each of which comprises a pair of right triangular frames 48 which are connected at their right angular vertices by a cross bar 49. The lower vertices of the triangular frames 48 are connected by a cross bar 50 the extending ends of which are pivotally connected to the chains 35 so that each of the cradles 47 is supported on these chains. Extending ends of the bar 49 form guide pins 51 which slide against inner faces of guides 41 as shown in Fig. 2.

25 When the chains 35 are caused to traverse their endless pathway by the rotation of shaft 31, each of the cradles 47 is caused to travel upwardly when it is disposed in the path 36, the cross bars 49 and 50 being guided at this time 30 between the back plate 37 and the inner edge portions of the guides 41. During this upward travel of a particular cradle 47, the center of gravity of that cradle, as well as any weight which might be imposed on it, maintains the pins 35 51 of such cradle pressed against the inner edge portions of the guides 41. Thus, as this cradle is propelled upwardly above the sprocket 31, it remains in the same rising position in which the rising cradle is shown in Fig. 1 until the pins 35 40 thereof engage traps 55 which start rocking this cradle rearwardly. The frames 48 of this cradle then engage the shaft 31 causing the cradle to flop backward until the pins 51 engage guides 45 as shown in Fig. 7.

45 Approaching the lower end of the chains 35, the downwardly moving cradle 47 is swung forwardly by engagement of the cradle frames 48 with a fixed bar 46. The center of gravity of the descending cradle 47 thus shifts forward of the cross bar 50 of this cradle with the result that the cradle swings over until the pins 51 thereof engage the lower ends of the guides 41. A complete cycle of travel of one of the cradles 47 has now been described.

55

The dumping mechanism 14

The dumping mechanism 14 includes a fruit receiving hopper 65 above which is supported a pair of rollers 66 and a roller 67 having arms 68 which are normally inclined downwardly. The roller 67 has a short arm 69 extending in the opposite direction from the arms 68, the arm 69 having a pin 70 which is trapped in an elongated eye 71 of a link 72, the lower end of which is pivoted on a short arm 73 fixed on a free end of the shaft 31 (see Figs. 1 and 5). Journaled on the frame 11 (see Figs. 1, 3 and 4) is a shaft 76 having a drive sprocket 77 and driven sprockets 78, the latter being connected by short endless chains 79 to small sprockets 80 mounted on stub shafts 81. Carried between the two chains 79 are dumping bars 82 and 83. A fulcrum bar 85 is fixed on the frame just outwardly from and 75 on the same level as the roller 67.

The empty box conveyer 15

The empty box conveyer 15 includes shafts 86 and 87 which are journaled on the frame 11 and provided with sprockets 88 and 89. Mounted on suitable stub shafts so as to be in alignment with the sprockets 88 and 89 are small sprockets 90 and 91, endless chains 92 encircling the sprockets thus in alignment. Carried by the chains 92 are a plurality of empty box conveying bars 93. Provided on the frame 11 are guide rails 96 for supporting the lower flights of the chains 92 and box rails 97 for supporting a box while it is being conveyed by one of the bars 93. For driving purposes the shafts 86 and 87 are connected by sprockets 98 and 99 rigidly fixed on these shafts and an endless chain 100 encircling these sprockets. It might also be pointed out here that the sprockets 88 are loosely mounted on the shaft 86 and the sprockets 89 are fixed upon the shaft 87.

Fixed on the rear end of shaft 86 is a spur gear 105 and a sprocket 106, the latter being connected with the sprocket 77 by a chain 107. Journaled in suitable bearings provided on the frame 11 is a shaft 108 having a spur gear 109 at one end which meshes with the spur gear 105 and at the opposite end a sprocket 110 and a drive pulley 111. The sprocket 110 is connected by an endless chain 112 to a sprocket 113 mounted on the front end of the shaft 31. The entire machine 10 is adapted to be driven by any suitable prime mover (not shown) by rotating the pulley 111 as by a belt 114.

Also fixed on the shaft 87 is a sprocket 118 which is connected by an endless chain 119 to a sprocket 120, the latter being fixed upon another shaft 121 also journaled on the frame 11. The shaft 121 has fixed thereon sprockets 122 which are connected by endless chains 123 to sprockets 124 provided on stub shafts 125 mounted on the frame 11. Attached to and carried between the chains 123 is a box-leveler cross bar 126. Pivotally mounted at 127 on the frame 11 is a stack latch 128 having a serrated foot 129 at its lower end.

The stacker 16 and empty stack conveyer 17

The stacker 16 includes a drive shaft 130 and stub shafts 131 having sprockets 132 and 133 which are connected by endless chains 134. United with the sprockets 133 on the stub shafts 131 are other sprockets (not shown) which are connected by endless chains 136 to drive sprockets 137 provided on a shaft 138 of the empty stack conveyer 17. Shaft 138 has sprockets 139 which are connected by endless chains 140 to sprockets 141, the latter being mounted on a shaft 142, and thence about other sprockets to carry the chains 140 about an endless path.

Secured on the end of the shaft 87 is a drive pinion 144 and in alignment with this is a sprocket 145 which is idly carried on a stub shaft 146 mounted on a bracket 147 directly over the shaft 87. The sprockets 144 and 145 are connected by an endless chain 148 to a sprocket 149 fixed upon the front end of the shaft 130 (see Fig. 4).

Provided on the frame 11 at the right-hand or front of the box stacker 16 are cradle guides 155. At the top of the stacker 16 is a pair of guides 157 and 158, the latter extending downwardly to the bottom of the stacker. The upper ends of the guides 158 have upwardly bent portions 159 which, as shown in Figs. 1 and 8, are secured to the upper ends of the guides 155.

The stack ejector 161

Pivots mounted on a shaft 160 is a stack ejector 161 which comprises a pair of vertical members 162, a cross member 163 connecting the upper ends of these, and a pair of elephant ears 164 as shown in Fig. 8. Provided on the shaft 160 is a weight 165 which tends at all times to return the ejector 161 to its reclining position in which its upper end rests in a recess provided in a frame member 166, as shown in Figs. 1 and 8. Also provided on shaft 160 are leaf springs 167 (see Fig. 1).

Carried between the chains 134 is a pair of stack forming cradles 170, each of these cradles comprising a pair of triangular frames 171 connected by a bar 172 at the lower vertices of the triangular frames 171. This bar has laterally extending ends 173 which pivotally connect with the chains 134 as shown in Fig. 8. Also provided on the triangular frames 171 are pins 174 and 175.

The manner in which the cradles 170 operate when the chains 134 travel about their endless path due to rotation of the sprockets 132 and 133 is as follows. When either of the cradles 170 is travelling downwardly with the forward flights of the chains 134, the guide pins 174 engage the guides 155 until the frames 171 thereof engage the shaft 160 which swings this cradle rearwardly. The leaf springs 167 are in alignment with the pins 174 and are now engaged by the latter to rock the cradle over with pins 174 in engagement with the guides 158. When either of the cradles approaches the uppermost end of the chains 134 the guide pins 174 of this cradle pass into the forwardly bent portions of the guides 157 and 158 and thus swing this cradle forwardly bringing the pins 175 thereof against the elephant ears 164 of the box stack ejector 161 as shown in broken lines in Fig. 8 and in full lines in Fig. 9. This shifts the box stack ejector outwardly into vertical position and causes the pins 174 to run out from between the forward ends of the guides 157 and 158 and travel upwardly along the inner faces of the guides 155. As the bar 172 of this cradle passes upwardly over the sprockets 132 so as to lift this cradle into its uppermost position, the pins 175 pass upwardly beyond the upper extremity of the elephant ears 164 thereby permitting the weight 165 to swing the stack ejector 161 back into its reclining position as shown in full lines in Figs. 1 and 8.

Operation

To set in operation the combined box stack dumper and empty box restacker 10, power is applied through the belt 114 to the pulley 111 so as to rotate the latter in the direction indicated by the arrows in Figs. 3 and 4. This rotates the shaft 108 which through the sprockets 110 and 113 and the chain 112 rotates the shaft 31 which sets in motion both the stack elevator 13 and the stack feeder 12. Also, through the gears 109 and 105, the sprockets 106 and 111, and the chain 101, the box dumping mechanism 14 is set in operation. As already noted, the rotation of the shaft 86 by the gears 105 and 109 transmits power through the sprockets 98 and 99 and chain 100 to the shaft 87, thus causing the conveyor 15 for removing empty boxes to be set in operation. Sprockets 118 and 120 and chain 119 cause the rotation of the shaft 121 and the functioning of the chains 123 and box-leveler cross bar 126 in a manner which will be described hereinafter. The sprocket 144 on the end of shaft 87 (see Fig. 4) drives the box stacker 16 through the chain 148 and the

sprocket 149. As above mentioned, empty box stack conveyer 17 is connected to the stacker 16 so that when the stacker is operated this also sets in motion the empty stack conveyer 17.

When the machine 10 has thus been started, the attendant trucks stacks of boxes S from their place of storage on the floor of the packing house and sets these down on the chains 21 of the feed conveyer 12 between the lugs 26 as shown in Fig. 1. The lugs 26 are so placed on the chains 21 that these stacks S are successively delivered, with the lowermost box in the stack extending into the elevating path 36, just as one of the cradles 47 rises upwardly into position to support this stack, tilts it into position in the path 36 against the back plate 37, and starts elevating it upwardly towards the box dumping mechanism 14. The latter mechanism is so timed that as each of the boxes B in a stack S being thus elevated comes into a certain position relative to the dumping mechanism, which may be termed a "dumping position", the bar 82 engages the side of this box and starts to tip it toward the right against angle iron fulcrum bar 85. As the bar 82 completes its tilting action on the side of this box, the bar 83 comes into play against the bottom of the box and continues the rocking of the latter with the result that the box is dumped over completely on its side, coming to rest temporarily in the position shown in broken lines 180 in Fig. 1.

After the box under discussion has remained in the position 180 a sufficient length of time for the fruit to gravitate entirely therefrom into the hopper 65, the arms 68 are lifted by the downward movement of the short arm 73 and the engagement of the upper end of the eye 11 with the pin 70 as shown in Fig. 7 in full lines. This lifts the box just as one of the cross bars 93 moves into contact with the empty box so that the latter is immediately shifted, as indicated by the broken lines 185 in Fig. 7, onto the rollers 66 and empty box rails 97.

As the first of the boxes is thus dumped and the empty box carried away by one of the bars 93, the next box of the stack is being lifted upwardly into dumping position which is indicated by the broken lines 186 in Fig. 7. As the box reaches this position the cross bar 82 moves into contact with the adjacent side of the box so as to initiate the dumping of this box as already described for the first box. In this manner the boxes of the stack S are successively elevated and dumped and the empty boxes propelled by conveying bars 93 of the conveyer 15 along the empty box rail 97 towards the stacker 16.

It is to be noted that the relatively rapid retraction of each of the cradles 47 from out of the path 36 just after the lowermost box of each stack has been delivered to the dumping mechanism 14 permits the next succeeding stack S to be tilted into place in the elevating path 36 so that the topmost box of the new stack is lifted into dumping position and is dumped with the same time interval between this and the dumping of the lowermost box of the preceding stack as elapses between the dumping of successive boxes in a given stack. Thus the dumping of fruit in the operation of my machine 10 is at a uniform rate, there being no fluctuation in the interval between the dumping of successive boxes so long as the feed conveyer 12 is kept supplied with stacks S.

As shown in Fig. 1, each of the empty boxes is propelled by one of the bars 93 into a position where this box is just beyond the right hand end 75

of the empty box rails 97 and disposed directly over the box stacker 16, after which this bar 93 passes around the sprockets 81 and then upwardly parallel with the bottom of the box. From the time that this box first starts to project over the right-hand ends of the rails 97 the top of the box is engaged by the box leveler bar 126 to support this box and prevent its falling to the right as the rails 97 are no longer under the center of gravity of the box. When this box is entirely free from the rails 97, however, it is then free to move downwardly and rock slightly into alignment with the box stacker 16.

Where this is the first box of a stack, one of cradles 170 will be found in its uppermost position as shown in full lines in Fig. 8 and this box will be deposited directly upon this cradle. As will be recalled, each cradle 170 when in its uppermost position has just swung the stack ejector 161 into vertical stack ejecting position as shown in Fig. 9, and then has released this to permit it to return to broken line position 162 as shown in Figs. 1 and 8. When this cradle, therefore, starts to move downwardly with the descending flights 25 of the chains 134, this first box of the stack is carried downwardly on this cradle outside of the stack ejector 161 as clearly shown in Fig. 1.

As successive boxes of a stack are dumped and the empties carried toward the right, as shown in Fig. 1, these are successively positioned as the second box is shown in Fig. 1 over the descending, partly formed stack of empty boxes and dropped on the preceding box and thus added to the stack so that eventually the entire stack of loaded boxes have been emptied and restacked in the formation of a stack of empty boxes. This occurs just as the other of the cradles 170 has returned upwardly to bring its pins 174 between the guides 157 and 158 thereby causing pins 175 of this cradle to engage the elephant ears 164 which shift the stack ejector 161 into vertical position and eject this newly formed stack onto the chains 140 of the empty stack discharge conveyor 17.

When thus ejected the stack is held against 45 rocking backward by engagement of the serrated foot 129 of the stack latch 128 with the upper box as shown in Figs. 1 and 8.

A complete cycle of operation of the machine 10 of my invention has now been described. This 50 cycle is repeated automatically as long as the feed conveyor 12 is supplied with stacks S of loaded boxes. While the stacker 16 of my invention is here shown as being used to stack empty boxes, and while these are shown as being stacked on 55 their sides, I do not desire my invention to be restricted to this use of the stacker 16 as this stacker may be used to stack loaded boxes in upright position if it is so desired.

While I have shown but a single embodiment of 60 my invention it is understood that many changes and modifications might be made in this and the invention embodied in many different forms with-

out departing from the spirit of the invention or the scope of the appended claims.

What I claim is:

1. In combination: means defining a stack forming path, said path being inclined from the vertical away from the direction towards which said stacks are to be delivered; endless chain means disposed substantially parallel with and adjacent said path; a plurality of stack supporting cradles pivotally mounted on said chain means; means for operating said chain means and guiding said cradles to cause each of said cradles in turn to be relatively quickly extended into said path adjacent its upper end, lowered through said path until adjacent the lower end of said path, swung out of said path, and elevated to a position adjacent the upper end of said path; means for delivering boxes at regular timed intervals into a position at the upper end of said path from which position said boxes are permitted to move downwardly to form a stack of boxes on each of said cradles as it travels downwardly through said path; and means for ejecting from said path each stack of boxes so formed in time to permit the one of said cradles disposed upwardly in said path to receive the next box from said position as the lowermost box in the next succeeding stack to be formed.

2. A combination as in claim 1 in which said stack ejecting means swings said stacks into vertical position in ejecting them from said path.

3. A combination as in claim 1 in which said stack ejecting means swings said stacks into vertical position in ejecting them from said path; and means for receiving said stacks from said ejecting means and conveying said stacks in close order away from said stack forming path.

4. A combination as in claim 1 in which said stack ejecting means is pivotally mounted adjacent the lower end of said path and extends rearwardly of said path while the stack is being formed in said path, said ejecting means being automatically swung into vertical position in delivering each stack from said path.

5. A combination as in claim 1 in which said stack ejecting means is pivotally mounted adjacent the lower end of said path and extends rearwardly of said path while the stack is being formed in said path, said ejecting means being automatically swung into vertical position in delivering each stack from said path; and means for automatically returning said ejecting means to its normal position behind said path immediately following the discharge of a stack of boxes so as to prevent said ejecting means interfering with the formation of the next stack of boxes.

6. A combination as in claim 1 in which said ejecting means is actuated to eject a stack from said path in response to the movement of one of said cradles into said path.

JAMES W. STEVENSON.
